UNITED STATES PATENT OFFICE.

JULIUS H. GUGLER, OF MINNEAPOLIS, MINNESOTA, ASSIGNOR TO BATTERY COMPANY, A CORPORATION.

BATTERY-CONTACT.

No. 914,038.

Specification of Letters Patent. Patented March 2, 1909.

Application filed February 21, 1908. Serial No. 417,021.

To all whom it may concern:

Be it known that I, JULIUS H. GUGLER, a citizen of the United States, residing at Minneapolis, in the county of Hennepin and State of Minnesota, have invented certain new and useful Improvements in Battery-Contacts; and I do hereby declare the following to be a full, clear, and exact description of the invention, such as will enable others skilled in the art to which it appertains to make and use the same.

My invention relates to electric batteries, and has for its object to provide an improved contact therefor.

To the above end, the invention consists of the novel devices and combinations of devices hereinafter described and defined in the claims.

One embodiment of the invention is illustrated in the accompanying drawings, wherein like characters indicate like parts throughout the several views.

Referring to the drawings: Figure 1 is a plan view, illustrating my invention. Fig. 2 is a transverse vertical section taken on the line $x^2 x^2$ of Fig. 1, some parts being broken away; and Fig. 3 is a detail showing the contact device on a larger scale than in the other views, but taken in section on the same line as Fig. 2.

This application discloses and claims a modification of the device generically claimed in a companion application Serial Number 417,020, filed by me of even date herewith; and, in this application, the numeral 6 indicates what, for the purposes of illustration, is designated as the negative electrode of the well known Bunsen type of battery, and the numeral 7 likewise indicates a porous earthen jar. This electrode 6, which is preferably a carbon or graphite electrode, is, as shown, provided with a flanged upper end that rests upon the upper edge of the jar 7. As shown, the said electrode 6 is of hollow cylindrical form, although it might take other forms so far as my invention is concerned. At one side and at its upper end, the electrode 6 is formed with a mercury containing well 8, the lower end portion of which is preferably contracted at 8^a so that it will contain but a small amount of mercury. In this well 8 is a body of mercury or other suitable conducting fluid, indicated by the character Y. The upper end of the well 8 is closed by a removable plug 9, preferably of inverted conical

form having a small axial opening through which the downwardly extended end portion 10^a of one of the battery leads 10 is extended into the body of mercury Y. This plug is preferably made of wood fiber, vulcanized rubber or other non-corrosive material. The lead preferably quite closely fits the axial perforation in the plug 9, but may be easily removed from working position or placed in working position. The plug 9 is so securely held in position, by surface friction or otherwise, that it will not be accidentally displaced, even if the electrode 6 be removed and turned upside down. In this connection it is important to note that the interior constructions of the well 8 and of the plug 9 are such that, when the electrode is thus placed in a horizontal position, all of the mercury will run into the down-turned side portion of the well, and will not rise to the height of the horizontally turned axial perforation of the plug 9, and when said electrode is turned upside down, the mercury will not rise on the plug to the height of the axial perforation thereof. This is, of course, due to the enlarged upper portion of the well and to the conical or tapered form of the plug. Such construction is important, because it prevents spilling and wasting the mercury when the electrode is removed from working position and laid in a horizontal or inverted position, as will be frequently done in practice.

The body of mercury Y forms a better electrical conductor between the lead and electrode than can possibly be obtained by a soldered joint or by a binding bolt and screw; and, in fact, forms a much better electrical connection than can be obtained in any other way.

Preferrably, the interior walls of the well 8 are electro-plated with copper or other metal, as indicated at 8^b. This gives the best possible adhesion between the mercury and an electrode constructed of carbon, graphite or similar material. The mercury used as a contact between the electrode and the lead is preferably covered with oil or water Y to prevent evaporation and oxidation.

A carbon electrode having a well containing mercury in direct contact with the carbon wall of said well is impractical, except when there is an extremely small ampere flow, approximately of one ampere or less, because there is no adhesion between the mercury and the carbon and, hence, there is

extremely high resistance; or, in other words, a very poor contact. It is, therefore, highly important that the walls of the mercury containing well formed in the carbon electrode be electro-plated with metal which will adhere to the carbon. Experiments demonstrate that copper is an extremely good material for electro-plating the walls of the well in the carbon electrode, because it is a good electrical conductor. It is true that copper will amalgamate, to some extent, with the mercury, but I have found in practice that such amalgamation does not produce injurious disintegration after being in continuous use for a period of eighteen months. I am unable to say what chemical action occurs which prevents all of the copper from being amalgamated with the mercury, but tests conducted for the purpose of determining the amount of copper amalgamated with the mercury show that the greatest amount of disintegration of the copper occurs the first few days after the mercury has been added; that this copper disintegration represents such a small quantity

that it does not injure the contact; and that after the first few days the disintegration of copper is so slow that it may be disregarded in practice. Other metals may be employed as the electro-plating metal, but advisably copper would be used in most instances.

What I claim is:

1. A carbon battery electrode formed with a well having a metal electro-plated surface and containing mercury, which mercury and electro-plated surface are adapted to form a contact between a lead and said electrode. 35

2. A carbon battery electrode formed in its upper extremity with a well, the walls of which are electro-plated with copper, and containing mercury, which mercury and copper electro-plated walls are adapted to form an electrical contact between a lead and said electrode. 40

In testimony whereof I affix my signature 45 in presence of two witnesses.

JULIUS H. GUGLER.
